UNITED STATES PATENT OFFICE.

PAUL E. HERRMANN, OF NEW YORK, N. Y., ASSIGNOR TO HERRMANN SUPPLY COMPANY INC., OF NEW YORK, N. Y., A CORPORATION OF NEW YORK.

STEAMING TUBE FOR PERMANENT WAVING.

Application filed February 9, 1928. Serial No. 253,024.

This invention relates to a steaming tube for use in conducting permanent waving operations.

It is desirable from the viewpoint of cleanliness, convenience in packing, and general attractiveness, that the means used to moisten and protect the hair during the heating of a permanent waving operation be susceptible of packing in a flat form, and be sufficiently inexpensive to permit them to be discarded after use in performing relatively few operations. It is also a fact that the chief curling effect in permanent waving is produced by securing a thorough steaming of the hair, with a relatively great quantity of steam. If sufficient steam is provided, the use of chemicals tending to stiffen and otherwise injure the hair, is obviated, or the concentration of the solution containing them is greatly reduced.

If steam in sufficient quantity is provided, the duration of the actual heating in a permanent waving operation is greatly reduced.

One object of the invention is therefore to provide an absorbent member for use in surrounding a coiled tress of hair in permanent waving, which is capable of absorbing a relatively great amount of moisture, and which comprises means for preventing escape of such moisture during the conduct of the operation.

Another object of the invention is to provide a member of this nature which comprises wholly fire proof and relatively steam proof, means for surrounding and enclosing the moisture absorbent portion of the member.

A still further object of the invention is to provide a member of this nature, which is so constructed that it may be packed or stored in a flat condition, but which when rolled will maintain a tubular form without the use of any externally applied fastening means.

In the accompanying drawings, Figure I is a plan view of the member constituting the steaming tube of the present invention, such member being shown in flat or extended condition; Figure II is a similar view of a modified form of steaming tube, which is designed particularly for use in curling the portion of a tress of hair lying closely adjacent the head of a subject; Figure III is a plan view showing a curling rod with a tress of hair wound thereon, and also showing the member at the beginning of the operation of winding it around the curling rod and coiled tress; Figure IV is a similar view, but shows the use

of the modified form of steaming tube illustrated in Figure II of the drawings, rather than the form shown in Figure I thereof; Figure V is a plan view showing the tube completely rolled around the coiling rod and tress of hair, such view being applicable to either the form of tube shown in Figures I and III, or the form of tube shown in Figures II and IV, and showing the end of the tube constricted and closed by means of a suitable closing clip or clamp; Figure VI is a cross sectional view through a strand of the fabric used in the outer portion of the steaming tube, such view being on a greatly enlarged scale to illustrate the construction of the strand; and Figure VII is a cross sectional view through the steaming tube, taken on a scale less than that of Figure VI but greater than that of the remaining figures of the drawings, and illustrating a modification for rendering the steaming tube wholly steam proof.

In the accompanying drawings the reference numeral 1 designates a strip, rectangular as shown, of flannel or other absorbent fabric. Secured to this strip, and overlapping same at 2, is a rectangular strip 3 of a relatively heavy asbestos fabric.

As shown in Figure III of the drawings, the steaming tube or member, which is indicated generally by the letter A, is used in conjunction with a curling rod 4 on which a lock or tress of hair 5 has been previously wound. The portion of the curling rod which carries the lock or tress 5, is surrounded by the portion 1 of the tube, such portion having been first thoroughly saturated with liquid. After all of the portion 1 has been rolled on the curling rod, the heavy outer portion 3 of the tube is in turn rolled thereon. The formation of a complete tube in this manner is illustrated in Figure V of the drawings. This figure of the drawings also shows the use of a clip 6, which has been caused to engage the end of the tube adjacent the head of the subject, to grasp the hair and curling rod, and completely surround the end of the tube.

In conducting a permanent waving operation, an electric heater is then caused to surround the curling rod. Sufficient heat is transmitted from this electric heater to thoroughly vaporize the moisture which has been absorbed by the absorbent fabric portion 1 of the tube A. The outer portion 3, however, prevents the transmission of sufficient heat to produce any scorching of the

hair 5 on the curling rod 4. It also serves to concentrate the effect of the steam on the coiled tress, and to provide a relatively great and continuous volume of such steam throughout the continuance of the heating.

In order that the outer portion 3 of the tube, and consequently the tube as a whole, may remain of itself in its rolled, or truly tubular position, this outer portion 3 is formed of a 10 special asbestos fabric, a magnified cross section of a strand of this fabric being shown in Figure VI of the drawings. As shown, it comprises one or more relatively light wires 7 of copper, or other suitable soft and flexible 15 metal, and a plurality of light asbestos cords 8. As the fabric of the portion 3, as a whole, is woven from strands combining asbestos cords and a flexible metal, the material tends to preserve any form into which it is forced. 20 When, therefore, the outer portion 3 is rolled to form an outer tubular covering, as shown in Figure V, this tubular form is maintained without the use of any special, and externally applied, fastening means.

25 The modified form of steaming tube shown in Figures II and IV of the drawings, comprises an outer portion 3^a, which is identical with the outer portion 3 shown in Figures I and III of the drawings.

30 The inner portion 1^a is of an equal length with the portion 1 of the previously described form, but of greatly decreased width. As shown in Figure IV of the drawings, a tress of hair may be wound on a curling rod 4^a, 35 so that only the portion 5^a adjacent the head of the subject is actually wound on the curling rod, leaving the remaining portion 5^a of the tress free. The narrower absorbent portion 1^a of the modified steaming tube B is 40 saturated with liquid, and is rolled around the coiled tress portion 5^a. The outer portion 3^a of the tube is then rolled around the tress and rod to cover the tightly wound portion 5^a of the tress, which is to be treated, and also 45 to cover the free portion 5^b of the tress, which is loosely coiled on the curling rod 4^a.

50 With the arrangement as described immediately above, only the tress portion which is to be curled is subjected to a steaming effect during the permanent waving operation, but the entire tress is protected from the effect of direct heat by the outer tube portion 3^a. This modified form of steam tube is of advantage where hair has grown out, without losing 55 the effect of a previous permanent waving operation. In such circumstances the hair remains waved adjacent its ends, but the new hair adjacent the scalp, which has never received a waving operation, is obviously un- 60 waved.

In the modification shown in Figure VII of the drawings, the absorbent portion 1^b of the steaming tube is identical with either the form shown in Figures I and III, or that

shown in Figures II and IV. The outer, or 65 protective, portion 3^b is also identical with that shown in the preceding figures in so far as its shape and position, and the internal structure of its strands, is concerned. The inner face of this portion 3^b is, however, provided with a rubberoid coating 9, which is 70 directly applied to and adheres to the fabric of this portion of the steaming tube. This facing 9 is wholly moisture proof, so that it 75 completely prevents the escape of steam during the permanent waving operation. As it is on the inner face of this outer or protective portion of the steaming tube, it is protected from a direct heating effect produced by an electric heater. If, therefore, this coating is 80 properly vulcanized to the face of the asbestos fabric, it will resist deterioration for a sufficient number of treatments to render its addition to the steaming tube practical.

85 The steaming tube of the invention, as described above, gives all the advantages of a flannel wrapping, when used in conjunction with a tube having an asbestos lining of relatively great thickness. It possesses in addition the advantage that a number of the tubes 90 may be packed in a relatively small container for shipment or storage. The greatest advantage of the tube, however, is that it gives a sufficient steaming of the hair, and an efficient protection from heat, by means of an 95 article which is relatively so inexpensive that it may be discarded after being used for a few times. This steaming tube, therefore, 100 does not become insanitary by the absorption of natural oils from the hair by many repetitions of its use in conducting hair waving treatments.

What I claim is:

1. A steaming tube for use in permanent waving comprising a strip of liquid absorbent material and a covering strip of fireproof fabric attached to the absorbent strip, said fireproof fabric having incorporated therein added material capable of maintaining the fabric in the form into which it is forced. 105

2. A steaming tube for use in permanent waving comprising a strip of liquid absorbent material, and a covering strip of fireproof fabric attached to the absorbent strip, said fireproof fabric having wires of a relatively soft metal woven therewith. 115

3. A steaming tube for use in permanent waving comprising a strip of liquid absorbent material, and a covering strip of fabric woven from strands comprising asbestos and a relatively soft metal attached to said absorbent strip. 120

4. A steaming tube for use in permanent waving comprising a strip of liquid absorbent material, a covering strip of fireproof fabric having incorporated therein added material capable of maintaining the form into which it is forced attached to said absorbent strip. 125

sorbent strip, and a coating of material impervious to vapors on one face of said fireproof fabric.

5. A steaming tube for use in permanent waving comprising a strip of liquid absorbent material, a covering strip of fabric woven from strands comprising asbestos and a relatively soft metal attached to said absorbent strip, and a coating of material impervious to vapors on one face of said fireproof fabric.

6. A steaming tube for use in permanent

waving comprising a strip of liquid absorbent material, a covering strip of fireproof fabric attached to the absorbent strip, said fireproof fabric having wires of a relatively soft metal woven therewith, and a coating of a material impervious to vapors on one face of said fireproof fabric. 15

In witness whereof, I hereunto set my hand.

PAUL E. HERRMANN.
